(57) **CLAIM**

The ornamental design for a leg support pillow, as shown and described.

DESCRIPTION

FIG. 1 is a front view of a leg support pillow showing my new design, a rear view being identical;

FIG. 2 is a right side view of the leg support pillow, a left side view being identical;

FIG. 3 is a top view of the leg support pillow;

FIG. 4 is a bottom view of the leg support pillow;

FIG. 5 is a top front side perspective of the leg support pillow; and,

FIG. 6 is a bottom front side perspective view of the leg support pillow in use.

The broken lines in FIG. 6 are illustrative of environmental structure forming no part of the claimed design.
